UNITED STATES PATENT OFFICE.

REUBIN N. ANDERSON, OF WHITE PLAINS, NEW YORK, AND ALFRED ROBINSON, OF CLEVELAND, OHIO, ASSIGNEES TO JOHN W. ELY, OF WHITE PLAINS, NEW YORK.

DESIGN FOR A CAR FOR AN AERIAL SWING.

56,685.

Specification for Design.

Patented Nov. 30, 1920.

Application filed March 12, 1920. Serial No. 365,324. Term of patent 7 years.

To all whom it may concern:

Be it known that we, REUBIN N. ANDERSON, a citizen of the United States of America, residing in the city of White Plains, in the county of Westchester and State of New York, and ALFRED ROBINSON, a citizen of the United States of America, residing in the city of Cleveland, in the county of Cuyahoga and State of Ohio, have invented a new, original, and ornamental Design for a Car for an Aerial Swing, of which the following description, in connection with the accompanying drawing, is a specification.

The several figures of the drawings are

perspective views of a car for an aerial swing showing our new design; Figures 1 and 2 being side views and Fig. 3 an end view.

Cars for aerial swings, to which this invention relates are usually suspended by cables from a rotatable support which is carried on a central pillar. Several such cars are usually suspended from the support.

We claim as our invention:

The ornamental design for a car for an aerial swing as shown.

REUBIN N. ANDERSON.
ALFRED ROBINSON.
